UNITED STATES PATENT OFFICE.

BENJAMIN F. MERRITT, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH-PRINTER.

1,295,998.

Specification of Letters Patent.

Patented Mar. 4, 1919.

Application filed May 11, 1918. Serial No. 233,914.

To all whom it may concern:

Be it known that I, BENJAMIN F. MERRITT, a citizen of the United States, residing at East Orange, in the county of Essex, 5 State of New Jersey, have invented certain new and useful Improvements in Telegraph-Printers, of which the following is a full, clear, concise, and exact description.

This invention relates to an improvement 10 in printing telegraph typewriters and particularly to a new and improved printing unit.

It has for its object to provide a simple, reliable and economically manufactured 15 printing unit, in which certain of the parts may be readily assembled, adjusted and removed when desired.

In accordance with the invention, the printing unit comprises a rigid frame to 20 which the printing magnet and its armature are attached. The armature is pivoted to the frame in a manner which permits of its particularly ready removal. The printing ram, which is part of the mechanism, and 25 operated by the movement of the armature, is mounted in suitable guides on a resilient member, which at its rear position is rigidly fastened to the frame of the printing mechanism. This resilient member extends 30 forwardly over the printing magnet and its forward end is adapted to be moved in two directions by means of adjusting screws which are suitably mounted in a forward position of the frame. The printing ram 35 may thus readily be adjusted with respect to the printing platen even while the typewriter is in operation.

The invention is disclosed in the drawing, of which Figure 1 is a plan view of the 40 printing unit; and Fig. 2 is a side elevation of the device.

As illustrated in the drawing, the device comprises a metallic frame 1, having front and rear portions 2 and 3, respectively, bent 45 up at right angles thereto and offset lugs 4, 4 provided with apertures through which extend suitable means to fasten the frame 1 to the main frame of the typewriter. Frame 1 is also provided to the rear and at the side 50 with bent-up ears 5, 5, which act as journals for the armature shaft as will be hereinafter

described. A printing magnet is attached to the forward bent-up portion 2 of frame 1, the windings 6 and 7 of which are energized at a suitable time and in a well-known 55 manner to attract an armature 8. The armature 8 is pivotally mounted on a shaft 9 which is journaled at each end in apertures in ears 5. Spacer washers 10 are placed around shaft 9 at each end thereof between 60 the armature 8 and the ears 5. In the retracted position, armature 8 bears against an adjustable back stop 11 in the form of a screw which extends through the rear bent-up portion 3 of the frame 1 and a plate 12, 65 the purpose of which plate 12 will be hereinafter described. The back stop 11 is provided with a suitable locking means in the form of a hexagonal nut 13. A spring plate 14 is fastened at one end to the frame 1 and 70 has two side flanges 15 at its rear which are adapted when in their normal position to extend in front of and close to the apertures in ears 5 and thereby prevent longitudinal movement of shaft 9. To remove shaft 9 all 75 that is necessary is to spring flanges 15 to one side and shaft 9 may be readily pushed out. This manner of fastening shaft 9 has the advantage of eliminating the necessity for cotter pins through the end of shaft 9 80 which break off and are difficult to remove readily when desired.

The printing ram 16 is slidably mounted in journal guides 17 and 18, attached to the forwardly extending portion of a resilient 85 member 19, the rear end 12 of which is bent downwardly and is fastened rigidly to bent-up portion 3 of frame 1. The resilient member 19 extends forwardly over the printing magnet in a line substantially midway 90 between the two windings 6 and 7. Integral with member 19 at the forward side portion thereof is a vertical plate 20. A spring 21 connected at one end to a pin 22 and at the other bearing against the front downwardly 95 extending portion 23 of member 19, surrounds ram 16 and tends to keep it in its rearmost position with its end resting against the armature 8 in its retracted position. The rear end 24 of the ram 16 is 100 rounded to provide a surface of contact with armature 8 which results in a minimum of

friction therebetween. The front guide 18 for ram 16 is attached to the downwardly extending portion 23 of member 19 and is in the form of a slotted cylinder. Ram 16 has a pin 25 extending therethrough which is adapted to slide in this slot and thus prevent any rotation of ram 16 as it reciprocates.

Attached to the front bent-up portion 2 of frame 1 is a plate 26 which extends upwardly therefrom. This plate 26 has two portions extending therefrom at right angles, a portion 27 which is bent into a horizontal plane over the front end of member 19, and a portion 28 which is bent parallel to and adjacent the side portion 20 of member 19. These portions 27 and 28 are provided with apertures through which extend adjustable screws 29 and 30 provided with suitable lock-nuts 31 and 32. The heads of screws 29 and 30 and nuts 31 and 32 are preferably hexagonal in shape to permit them to be readily adjusted. It will be noticed that the offset portions 27 and 28 of plate 26 are so bent as not to prevent access to the screws 29 and 30 and nuts 31 and 32 from the front of the machine so that these may be readily adjusted with a wrench. The end of screw 29 is adapted to bear against the forward upper face of member 19 and the screw 30 against the face of plate 20. The member 19 is so designed that its resiliency causes it to tend to press firmly against screws 29 and 30. The forward end of ram 16 is preferably squared and provided with a rubber cap 33. A type wheel or platen 34 is located adjacent the end of ram 16 and it is to keep the squared end of ram 16 in proper aligned relation with platen 34 that this device is intended.

40 In the operation of the device, whenever the printing magnet is energized, armature 8 is attracted and throws ram 16 forward with considerable force against the platen 34. Spring 21 returns the ram to its normal position carrying armature 8 back with it against the back stop 11. Whenever it is found that the characters are not being properly printed because of the fact that the ram and plate are not properly aligned, the screws 29 and 30 are moved to spring the front end of member 19, thereby moving ram 16 in the direction necessary to cause the proper alignment.

What is claimed is:

55 1. In a telegraph printer, a printing unit comprising a frame, a spring plate having one end free and the other end rigidly attached to said frame, a printing ram slidably mounted in guides along the free portion of said spring plate, and adjusting means mounted on said frame and adapted to cooperate with the free end of said spring plate to move said free end and change the direction of the axis of the printing ram.

2. In a telegraph printer, a printing unit 65 comprising a frame, a printing magnet mounted on said frame, a spring plate having one end free and the other end rigidly attached to said frame, a printing ram slidably mounted in guides along the free portion of said spring plate and extending over said printing magnet, an armature actuated by said printing magnet and adapted to actuate said printing ram, and adjusting means mounted on said frame and adapted 70 to cooperate with the free end of said spring plate to move said free end and change the direction of the axes of the printing ram.

3. In a telegraph printer, a printing unit 80 comprising a frame, a spring plate having one end free and the other end rigidly attached to said frame, a printing ram slidably mounted in guides along the free portion of said spring plate, and a pair of adjusting screws having axes at right angles 85 to each other and mounted on said frame, said adjusting screws adapted to contact and cooperate with the free end of said spring plate to move said free end and adjust the printing ram.

4. In a telegraph printer, a printing unit comprising a frame, a printing magnet mounted on said frame, a spring plate having one end free and the other end rigidly attached to said frame, a printing ram slidably mounted in guides along the free portion of said spring plate and extending over the printing magnet, an armature actuated by said printing magnet and adapted to actuate said printing ram, and a pair of 95 adjusting screws having their axes at right angles to each other and mounted on said frame, said adjusting screws being adapted to contact and cooperate with the free end of said spring plate to adjust the printing 100 ram.

5. In a telegraph printer, a printing unit 110 comprising a frame, a printing magnet mounted on said frame, a spring plate having one end free and the other end rigidly attached to said frame, said free end extending forwardly over the printing magnet, a printing ram slidably mounted in guides along the free portion of said spring plate, an armature mounted on said frame and actuated by said printing magnet, said armature contacting with and adapted to move said printing ram in the printing direction, resilient means connecting said frame and said ram and adapted to return the ram to normal condition after its activation, and a pair of adjusting screws having their axes at right angles to each other and mounted on said frame, said adjusting screws adapted to contact and cooperate with the free 120 end of said spring plate to adjust the printing ram.

6. In a telegraph printer, a printing unit

comprising a frame, a printing ram, a printing magnet mounted on said frame, an armature actuated by said printing magnet and adapted to coöperate with said printing ram, a shaft on which said armature is pivoted said shaft at each end being journaled in portions of the frame, and a spring

plate attached at one end to the frame and having free end portions adapted to lie adjacent to each end of said shaft to prevent longitudinal motion thereof.

In witness whereof, I hereunto subscribe my name this 8th day of May, A. D., 1918.

BENJAMIN F. MERRITT.
